UNITED STATES PATENT OFFICE.

ARVID PETERSON, OF TRENTON, NEW JERSEY, ASSIGNOR TO DE LAVAL STEAM TURBINE COMPANY, OF TRENTON, NEW JERSEY, A CORPORATION OF NEW JERSEY.

DEEP-WELL PUMP.

Application filed November 22, 1924. Serial No. 751,490.

My invention relates to pumps adapted for pumping from relatively deep wells, that is, wells the depth of which precludes the placing of the pump at ground level.

More particularly, my invention relates to pumps of the centrifugal type and more particularly adaptable for pumping water.

Heretofore in the pumping of wells, the depth of which exceeds thirty feet, it has been necessary to place the pump at the bottom of the well or within about thirty feet thereof, in order to obtain suction, and to actuate the pump by means of shafting which affords a connection between the pump

and engine or motor at ground level. Such a construction naturally requires shafting of a length equal to the depth of the well, which, when the well is of any considerable depth, presents difficult problems to prop-

erly support the shafting to avoid whipping and to effect its proper lubrication. Such construction has been found to be relatively inefficient, since the long shaft can only be driven at relatively low speed, necessitating the use of a pump having a considerable number of stages even for a comparatively moderate head.

Now it is the object of my invention to provide a centrifugal pump for deep wells combined with a turbine for driving it as a self-contained unit, which may be positioned at the bottom of a well.

Further objects of my invention are to produce a combined turbine pump which will be self-lubricated and automatically balanced, and of such a structure as will enable its economical production and a high degree of efficiency and durability in operation.

Having now indicated, in a general way, the nature and purpose of my invention, I will proceed to a detailed description thereof with reference to the accompanying drawings, in which I have illustrated a preferred embodiment, and in which—

Fig. 1 is a sectional view of a pump embodying my invention.

Fig. 2 is a sectional view of a modification of the structure shown in Fig. 1.

Referring to Fig. 1, *a* indicates a casing within which a combined pump and turbine casing *b* is secured by threaded engagement and which, extending to a desired point of delivery, serves as a discharge pipe for the pump. Mounted in rubber-lined bushings *c*

in the casing *b* is a shaft *d* which passes through a partition *e*, serving to divide the casing and provided with ports controlled by check valves *g*. Connected to the upper end of the casing *b* is a water supply pipe *f* adapted to lead a supply of water, at sufficient head, to the casing in which it passes through a diffusing passage *h* to a turbine wheel *i* secured on shaft *d*. The discharge from the first wheel *i* passes through a second diffusing passage *h* to a second turbine wheel *i*, from which the water passes into the discharge pipe *a*, above the partition *e*.

Below the partition a pump impeller *j* is secured to shaft *d* and communicates with a suction opening *k*. The discharge from the impeller passes through check valve *g* and mixes with the water from the turbine wheels.

The combined turbine and pump rotor, that is, shaft *d*, turbine wheels *i*, *i* and impeller *j*, is carried on a hydraulic balancing arrangement comprising a balancing disc *l* adapted to be supported between a depending flange *m* and an internal flange *n* on the casing by the pressure of the water supply for turbine wheels *i*, *i*. Above the disc *l* is formed an equalizing chamber *o* in communication with the water supply through the space between flange *n* and the under surface of disc *l* and in communication with a leak-off pipe *p* connected to the suction opening *k*, through the space between depending flange *m* and the upper surface of the disc *l*, through annular passage *q* about shaft *d*.

The operation of the pump will, it is thought, be obvious, it being understood that the casing *b* is positioned at the bottom of a well. Water at sufficient head is admitted to the turbine wheels, causing them to rotate the impeller, which forces water, drawn from the suction inlet through check valves *g*, into the discharge pipe where it picks up the water leaving the lower turbine wheel, the whole being discharged to the desired point through the discharge pipe. It will be noted that the check valves *g* will prevent the passage of water from the turbine wheel *i* to the pump in the event that the pump should lose its prime.

When the water supply enters casing *b*, it exerts a pressure on balancing disc *l*, which causes the rotor to be lifted until communication between chamber *o* and the

leak-off pipe is shut off by the disc seating on flange *m*. Water from casing *b* then bypasses disc *l* and pressure builds up on the top of the disc until, with the addition of the weight of the rotor, it overcomes the pressure on the underside of the disc. The rotor then sinks, causing communication to be opened between chamber *o* and the leak-off pipe, with the result that the pressure on the top of the disc falls. The disc then assumes a position in which the communication of chamber *o* with the leak-off pipe will be such that a balance will be effected between the pressure beneath the disc and that above combined with the weight of the rotor.

In operation, the casing *b* will be filled with water which will work into and effectively lubricate rubber-lined bushings *c*. In the case of the upper bushing, water will work down along the shaft from the top of the bushing to which it has access through a passage *u* affording communication with the supply pipe, and in the case of the lower bushing, water supplied from the discharge of the impeller through a pipe *v* will work upward along the shaft.

Referring now to Fig. 2, in which I have shown a modified structure comprising a discharge pipe *a'* and a pump casing built up of superimposed sections *b'* secured together by means of bolts *s*: The casing serves to support in rubber-lined bushings *c'* a shaft *d'* upon which is mounted two turbine wheels *i'*, receiving a supply of water through a supply pipe *f'*, through diffusing passages *h'*, and two impellers *j'*, the lower one of which draws water through a suction opening *k'* and discharges into the upper one which discharges the water into the discharge pipe when the water from the lower turbine wheel is picked up and the whole discharged.

The turbine wheels *i'* and the impellers *j'* are adapted to run on annular bearing rings *t* and the shaft *d'* is supported by a hydraulic balancing device similar to that described above in reference to Fig. 1.

It will now be clear that by virtue of my invention I have provided a self-contained, self-lubricated pump turbine unit of high ef-

ficiency and operable with the elimination of the difficulties heretofore presented in deep well pumping.

It will be understood that various structural modifications may be made in the device described and that the number of turbine wheels and impellers may be varied to meet the requirements of conditions without departing from the spirit of my invention.

I claim—

1. A deep well pump comprising a casing, a shaft mounted in said casing, a turbine wheel mounted on said shaft, an impeller mounted on said shaft, a partition dividing said casing between said turbine wheel and said impeller, a port in said partition and means adapted to receive water discharged from said turbine wheel and from said impeller.

2. A deep well pump comprising a casing, a rotor including a turbine wheel and an impeller mounted in said casing, a partition provided with a port dividing said casing between said turbine wheel and said impeller and means for controlling the port in said partition.

3. A deep well pump comprising a casing, a rotor including a turbine wheel and an impeller, separate means for supplying water to the turbine wheel and to the impeller, a partition provided with a port separating said impeller from said turbine wheel and a discharge pipe common to both.

4. A deep well pump comprising a casing, a rotor including a turbine wheel and an impeller, a partition in said casing extending between the turbine wheel and the impeller and provided with a port, a discharge pipe adapted to receive water discharged from said turbine wheel and water discharged from said impeller through said port, and a check valve adapted to prevent water discharged from said turbine wheel from entering said impeller.

In testimony of which, I have hereunto set my hand, at Trenton, New Jersey, on this 19th day of November, 1924.

ARVID PETERSON.
